UNITED STATES PATENT OFFICE.

DENNIS F. SPILLANE, OF TOLEDO, OHIO, ASSIGNOR TO THE LIBBEY GLASS COMPANY, OF TOLEDO, OHIO, A CORPORATION OF OHIO.

DESIGN FOR A CUT-GLASS VESSEL.

No. 38,002.

Specification for Design.

Patented May 8, 1906.

Application filed March 26, 1906. Serial No. 308,183. Term of patent 7 years.

To all whom it may concern:

Be it known that I, DENNIS F. SPILLANE, a citizen of the United States of America, residing at Toledo, in the county of Lucas and State of Ohio, have invented a certain new, original, and ornamental Design for a Cut-Glass Vessel, of which the following is a specification, reference being had therein to the accompanying drawing, forming part thereof.

The figure is a perspective view of a cut-glass dish, showing my new design.

I claim—

The ornamental design for a cut-glass vessel, as shown.

DENNIS F. SPILLANE.
